UNITED STATES PATENT OFFICE.

WILLIAM C. ANDERSON, OF CHICAGO, ILLINOIS, ASSIGNOR TO THE LIBBEY
GLASS COMPANY, OF TOLEDO, OHIO, A CORPORATION OF OHIO.

DESIGN FOR A GLASS DISH.

SPECIFICATION forming part of Design No. 35,830, dated April 1, 1902.

Application filed March 10, 1902. Serial No. 97,642. Term of patent 7 years.

To all whom it may concern:

Be it known that I, WILLIAM C. ANDERSON, a citizen of the United States, residing at Chicago, in the county of Cook and State of Illinois, have invented and produced a new and original Design for Glass Dishes, of which the following is a specification, reference being had to the accompanying drawings, forming part thereof.

Figure 1 is a bottom view of a glass dish, showing my new design. This figure shows the ornamentation of one quarter only of the dish; but it is understood that the decorations shown are repeated in the other three quarters. Fig. 2 is a view in elevation, portions being broken away to show the contour of the dish in vertical section.

As shown in the drawings, the leading or material feature of my design consists of the deep crossing grooves *a a* at intervals around the sides of the dish, from which shallower grooves *b* are branched, giving an appearance of crossed feathers. Between the feather decorations are the rosettes or many-pointed

stars *c c*, above which are the fan-shaped figures *d*, each rosette *c* appearing to hang from the center of the fan-shaped figure above it. Smaller rosettes *c'* are shown between the crossed main grooves of the feather decorations. The center of the bottom of the bowl is ornamented with a star decoration *e*. All the decorations referred to are formed by grooves in the glass, such as are characteristic of cut-glass ware in general.

Having described my invention, what I claim as new, and desire to secure by Letters Patent, is—

The design for a glass dish as herein shown and described.

In testimony whereof I have signed my name to this specification, in the presence of two subscribing witnesses, this 3d day of March, A. D. 1902.

WILLIAM C. ANDERSON.
